UNITED STATES PATENT OFFICE.

EDNA V. BRATTON, OF LURAY, KANSAS.

POULTRY-FUMIGATOR.

1,215,336.

Specification of Letters Patent. Patented Feb. 13, 1917.

Application filed August 7, 1916. Serial No. 113,678.

To all whom it may concern:

Be it known that I, EDNA V. BRATTON, a citizen of the United States, residing at Luray, in the county of Russell, State of Kansas, have invented certain new and useful Improvements in Poultry-Fumigators; and I do hereby declare the following to be a full, clear, and exact description of the invention, such as will enable others skilled in the art to which it appertains to make and use the same.

This invention relates to insect destroyers of the type which are commonly known as "poultry fumigators."

One important object of the invention is to improve and simplify devices of this character so that means are provided for conveniently fumigating all kinds of poultry to destroy lice and disease germs that locate among the feathers of the fowls, by the use of burning charcoal with or without such antiseptics as burning sulfur or the like.

Another important object of the invention is to provide a device of this character wherein the body of the fowl is held within the device while the head protrudes therefrom and is held by a flexible collar so connected to the device that it may be readily removed for the purpose of cleansing the same and then as readily replaced.

Another important object of the invention is to provide means for regulating the burning of the combustible.

With the above and other objects in view, as will be hereinafter apparent the invention consists in general of certain novel details of construction and combinations of parts hereinafter fully described, illustrated in the accompanying drawing, and specifically claimed.

In the accompanying drawings, like characters of reference indicate like parts in the several views, and:

Figure 1 is a vertical section taken through the center of the device showing the fowl in position therein.

Fig. 2 is a detail sectional view showing the under side of the lid, the view disclosing that portion of the lid wherethrough the fowl's neck protrudes.

Fig. 3 is a section on the line 3-3 of Fig. 1.

Fig. 4 is a section on the line 4-4 of Fig. 1.

In the embodiment of the invention herein illustrated there is shown and provided a

cylindrical casing 10 having a bottom 11. To the top of this casing is hinged a closure 12 having a depending flange 13 surrounding the top of the casing so as to fit tightly thereto. To one side of the flange 13 is connected the hinge 14 which secures the top to the casing while opposite this hinge there is provided a finger grip 15. Extending across the casing about seven and one-half inches below the top 12 is a sheet of heavy galvanized fabric 16 upon which the fowl may rest. The top of the casing is provided with an opening 17 through which the fowl's neck protrudes and surrounding this opening 17 on the inside of the top is a depending flange 18 concentric to which is a hoop or ring 19 so that the lower edges of a fabric cylinder, preferably of rubberized fabric, and indicated at 20 may be grasped between the hoop 19 and flange 18 and thus retain its proper relation to the top 12. The upper end of this fabric element is provided with a draw string 21 so that it may be caused to fit tightly around the hen's neck as shown.

At one side of the lower part of the casing there is provided an opening 22 and slideable in this opening is a drawer 23 having an open top and a bottom 24 provided with a series of openings 25. This drawer rests on a shelf 26 provided with openings 27 which, when the drawer is fully pushed in, register with the openings 25 so that a draft may pass up through said openings 27 and 25. Above the opening 22 is a guard flange 28 so that the drawer may be pulled slightly out without opening the device to the air, the drawer itself being provided with a coacting guard flange 29. By pulling the drawer slightly out the openings 25 may be caused to move out of registry with the openings 27 and thus close off the draft through said openings.

Located above the drawer and in spaced relation thereto is a shield plate 30 having a downwardly extending flange 31 which surrounds the drawer and prevents any flame from the drawer reaching the upper part of the casing and burning the fowl.

In using the device, the fowl is placed on the screen 16, the top being of course open, and the top is then shut down and the fowl's neck brought through the opening therein. The fabric cylinder 20 is fitted over the fowl's neck and the draw string 21 drawn sufficiently tight to prevent the escape of any fumes from the interior of the cas-

ing around the neck of the animal. A charcoal brick or the like indicated at 32 is then placed in the drawer and the latter pushed into position after the brick has been ignited. 5 In addition to this brick there may be flowers of sulfur or other like fumigating agents placed in the drawer therewith. If it is desired to produce a rapid combustion of the brick the drawer is pushed fully in as shown 10 but this combustion can be regulated by the extent to which the drawer is shoved into position. The fumes of the combustible rising from the brick then pass through the open top of the drawer around the edges 15 of the flange 31 and up till they surround the body of the fowl and there kill the noxious insects or germs.

After the fowl has been fumigated a sufficient time the brick is withdrawn and the 20 fowl removed.

There is thus provided a simple and efficient device of the kind described and for the purpose specified.

It is obvious that many minor changes 25 may be made in the form and construction of the invention without departing from the material principles thereof. It is not therefore desired to confine the invention to the exact form herein shown and described

but it is wished to include all such as 30 properly come within the scope claimed.

Having thus described the invention, what is claimed as new, is:—

1. In a fowl fumigator, a casing, a top hinged to said casing and having an opening therethrough for the protrusion of a fowl's neck, a foraminous platform below said top on which the fowl rests, a drawer for combustibles slidable into and out of the lower part of said casing, and a flame 40 deflecting shield mounted within the said casing over said drawer.

2. In a device of the kind described, a casing having a drawer receiving opening in one side, a supporting plate for a drawer located in the casing flush with the lower edge of the opening and provided with a series of openings therein, a drawer slidable into said opening and having a bottom provided with openings adapted to be brought 45 into registry with the openings in the plate.

In testimony whereof, I affix my signature, in the presence of two witnesses.

EDNA V. BRATTON.
